UNITED STATES PATENT OFFICE.

CHARLES D. ORCUTT, OF DAYTON, OHIO.

DESIGN FOR A STOOL-LEG.

SPECIFICATION forming part of Design No. 36,281, dated April 7, 1903.

Application filed July 14, 1902. Serial No. 115,601. Term of patent 3½ years.

To all whom it may concern:

Be it known that I, CHARLES D. ORCUTT, a citizen of the United States, residing at Dayton, in the county of Montgomery and State of Ohio, have invented a certain new, original, and ornamental Design for a Stool-Leg; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 Figure 1 is a side elevation showing my new design for a stool-leg. Fig. 2 is a front elevation. Fig. 3 is a top plan view.

As shown in the drawings, the leading or material feature of my invention consists in 20 a leg for a stool, the same having two degrees of curvature and the surface of which is provided throughout with ornamentations consisting of raised surfaces inclosed by curve or wave lines, which extend from the opposite 25 edges of the leg inwardly and terminate on

either side of the longitudinal center of the leg, the longitudinal edges of the legs having a margin C, which extends throughout said edges. A series of raised surfaces D are inclosed by lines E, the said lines being in the form of wave-lines and extending from the marginal edges upwardly in oblique lines. The upper end of the leg terminates in a flat portion F, from which project spurs G G. The upper end of the leg has a 35 wider diameter than the lower end thereof, and the said lower end terminates in a foot H of rounded form.

Having described my invention, what I claim as new, and desire to secure by Letters 40 Patent, is—

The ornamental design for a stool-leg as herein shown and described.

In testimony whereof I affix my signature in presence of two witnesses.

CHARLES D. ORCUTT.
